UNITED STATES PATENT OFFICE

ARTHUR F. PYM, OF SWAMPSOFT, MASSACHUSETTS, ASSIGNOR TO UNITED SHOE MACHINERY CORPORATION, OF PATERSON, NEW JERSEY, A CORPORATION OF NEW JERSEY

SMOOTHING MACHINE

Application filed January 14, 1929. Serial No. 332,477.

This invention relates to machines for shaping shoes, and particularly for shaping the uppers of turn shoes into conformity with the last after the turning and relasting operations.

In relasting a turn shoe, the upper is not drawn over the last with the same tension as that to which it is subjected in the original lasting operation and, accordingly, it does not conform closely at all points to the shape of the last. Further, in forcing a last into a shoe while the latter is in temper, or slightly moist, wrinkles are very likely to be formed adjacent to the seam. It is, therefore, customary to submit the upper to a blocking or smoothing operation in order to eliminate the wrinkles and shape the upper to the last, particularly where it passes over the corner of the last.

It is an object of the invention to provide an improved machine for use in performing the above operation.

One feature of the invention consists in the provision, in a machine of the type referred to having a tool shaped to conform substantially to the portion of a lasted upper adjacent to the last corner, that is, the junction of the bottom and side faces, of resiliently operated means for causing the tool to impinge upon a shoe held thereagainst in order that the portion of the upper adjacent to the last corner shall be conformed smoothly to the last. As herein illustrated, the above-mentioned resiliently operated means comprises a hammer and mechanism constructed and arranged rapidly to oscillate the hammer into contact with a holder for the tool, thereby imparting to it a series of impacts.

In order that the tool shall always be flatly seated against the work, the illustrated connection between the tool and its holder is constructed and arranged to allow the tool to adjust itself in the holder in accordance with changes in contour and in the position of the work held thereagainst as the point of operation of the tool on the work is transferred thereabout. To this end the invention includes the provision of a rotatable mounting for a tool of the type referred to in a holder. Another feature of the invention comprises

means for resiliently resisting the movement of the tool in the holder from a predetermined angular relation with respect to the holder in order that the tool shall always resume its initial position as soon as the work is removed from the tool.

These and other features of the invention will be best understood and appreciated from the following description of a preferred embodiment thereof, selected for purposes of illustration and shown in the accompanying drawings, in which

Fig. 1 is a view of the machine in side elevation, partly in section; and

Fig. 2 is a view in perspective of the tool and its holder in operative relation to a shoe.

The illustrated machine comprises a column 10, of which only the upper portion is shown, and an overhanging head 12 having a casing 14 within which the mechanism of the machine is contained. A transverse shaft 18 is journaled in the head of the machine and is arranged to be driven through a pin clutch of usual commercial construction, of which the pin 20 is shown in Fig. 1 and with which the pin shifting finger 22 cooperates. The finger 22 is mounted to swing about the axis of a shaft 24 journaled in the upper portion of the machine frame 12 and is controlled by the operator through an arm 26 and a vertical treadle rod 28. It will be understood that when the treadle rod is depressed, as in Fig. 1, the clutch pin is moved by the finger 22 into an inoperative position but when the treadle rod is elevated by the operator and the shifting finger 22 swung outwardly, the pin acts automatically to engage the clutch and, consequently, to set the shaft 18 in rotation. The details of the clutch are not further illustrated herein as clutches of this type are well-known in the art.

The tool holder comprises an arm 30 pivotally mounted at its inner end upon a transverse stud 32 in the machine head 12 and normally maintained at rest against a positive stop 34 by means of a compression spring 36 interposed between its under surface and a boss in the head 12. The holder is thus normally located in a predetermined elevated position, although it is free to move down-

wardly against the compression of the spring 36.

The outer end of the holder 30 is cylindrical in shape and provided with a longitudinal bore to receive the cylindrical shank 37 of a tool 38. At its inner end, the shank 37 is provided with a transverse slot 40 having a flat bottom. The holder 30 is provided with an upstanding boss 42 in which is located a plunger 44, normally pressed downwardly against the bottom of the slot 40 by a compression spring 46 confined within the boss 42 by a cotter pin, as shown. The lower end of the plunger 44 is substantially flat and tends to maintain the shank 37 of the tool in a corresponding angular position but it will be apparent that the plunger 44 will yield upwardly and permit a temporary angular displacement of the shank 37. The tool 38, which may be termed a blocking tool, has a relatively wide horizontally-disposed lower surface curved somewhat to conform with the general outline of the side of a shoe and adapted to engage a substantial area of the upper adjacent to the last corner. At its outer end, the tool is provided with a downwardly extending lip or rib 39 which may extend into the crease between the upper and the sole. The tool 38, accordingly, is shaped to fit about the last corner and may be said to have a re-entrant vertex formed by the juncture of its lower surface with the downturned lip 39.

Above the tool holder 30 and within the casing 14 is mounted a hammer 50 arranged to swing about the axis of a transverse stud 52 carried by the head of the machine and having a head 54 formed at its free end which is arranged when operated to strike the outer end of the holder 30 at a point adjacent to the blocking tool 38 and impart a sharp downward blow thereto. The hammer 50 has a downwardly extending arm 56 to which is connected a tension spring 58, secured at its rear end to an adjustable stud 60 projecting through the column 10 and provided at its outer end with an adjusting nut 62 and a lock nut. By turning the adjusting nut 62, the stud 60 may be drawn in or out and the tension of the spring 58 correspondingly adjusted to vary the impact of the hammer.

The hammer 50 is also provided with a rearwardly extending cam arm 55 which cooperates with a spiral cam 64 to lift the head of the hammer against the tension of the spring 58. The spiral cam 64 is provided with an abrupt drop-off and arranged to rotate in a clockwise direction, as shown in Fig. 1, so that when the drop-off point in the cam is reached, the cam arm 55 of the hammer is released and the spring 58, which has been gradually tensioned in the rotation of the cam, is free to cause the hammer to impinge upon the holder 30 for the blocking tool.

The shaft 18 carries a brake disk 66 with which cooperates a brake shoe 68 mounted

eccentrically upon the transverse shaft 24 and being operated by the treadle rod 28 so as to release the brake disk 66 when the clutch is tripped and to engage the brake disk and stop the rotation of the shaft 18 when the treadle rod is released and the clutch disengaged. The brake 68 also serves to prevent reverse rotation of the shaft 18 which might otherwise be caused by the pressure of the cam arm 55 of the hammer upon it.

The operation of the machine will be apparent from the foregoing description but may be summarized as follows: The operator presents the shoe in the position indicated in Fig. 1, with the sole substantially vertical and with the blocking tool overlying the side of the upper and substantially fitting the last corner. As the tool is positively supported in stationary initial position, the operator may press the shoe against it without imparting any movement to the tool beyond a swivelling movement of angular displacement which brings the surface of the tool into conformity to the contour of the work. Having thus positioned the shoe, the operator will trip the clutch and set the shaft 18 in rotation. The hammer 50 is thereupon swung to its highest position and released by the cam 64 in rapid succession and a series of sharp hammer blows are thus imparted to the holder 30, which drives the tool downwardly against the lasted shoe and thus shapes the upper in conformity with the last and eliminates any wrinkles which may have been caused by the relasting operation. The operator proceeds to move the shoe longitudinally with respect to the tool 38 as the hammer 50 continues to vibrate and to impart a corresponding vibration to the tool 38 about its axis of movement upon the stud 32. It will be seen that each vibration of the tool begins from a definite point of rest or initial position determined by the stop 34 and that the tool is returned to initial position between consecutive vibrations. The operator continues to move the shoe with respect to the tool 38 until he has presented thereto substantially the whole of its forepart portion adjacent to the sole edge and until the upper has been entirely smoothed and brought into conformity with the lines of the last. The treadle rod is then released and the machine comes to rest with the tool holder 30 in initial position, as before.

While a blocking tool of the characteristics herein disclosed may be used with particular advantage in a machine organized to vibrate a tool from a predetermined initial position of rest, it would be within the scope of the invention to utilize tools of whatever shape may be best suited for the requirements of the work in hand.

Having thus described my invention, what I claim as new and desire to secure by Letters Patent of the United States is:

1. A shoe shaping machine, having in combination, a tool shaped substantially to fit the side of the upper adjacent to the last corner of a relasted turn shoe, and resiliently operated means for causing the tool to impinge upon a shoe held thereagainst. 70
2. A shoe shaping machine having, in combination, a tool shaped to engage the side of the upper of a relasted turn shoe and extend over the corner of the last, a holder for the tool, and means for causing the tool to impinge upon a shoe held thereagainst comprising a resiliently operated hammer constructed and arranged to contact with said holder. 75
3. A shoe shaping machine having, in combination, a tool shaped to conform substantially to the portion of a lasted upper adjacent to the last corner, a holder for said tool arranged to allow the tool to adjust itself in said holder in accordance with changes in the contour of the work and the position of the work as it is presented to the tool, and means for imparting resilient impacts to said holder to cause said tool to impinge upon the work. 80
4. A shoe shaping machine, having in combination, a tool with a laterally extending face conforming substantially in shape to the side of an upper adjacent to the last corner, and arranged to swivel about a longitudinal axis when in operative position, and means for vibrating the tool about a transverse axis. 85
5. A shoe shaping machine, having in combination, a tool with a laterally extending face conforming substantially in shape to the side of an upper adjacent to the last corner, means for yieldingly maintaining said tool in normal angular position but permitting it to be temporarily displaced about a longitudinal axis by pressure of the work, and means for vibrating said tool from a predetermined initial position. 90
6. A shoe shaping machine, having in combination, a frame having a pivotally mounted holder therein, a blocking tool rotatably mounted in the holder, means for yieldingly urging said tool toward a predetermined position with respect to said holder, and resiliently operated means for striking said holder to cause the tool to impinge upon a shoe presented thereto. 95
7. A shoe shaping machine, having in combination, a holder for a blocking tool, and mechanism for subjecting said holder to recurring resilient impacts. 100
8. A shoe shaping machine, having in combination, a holder for a blocking tool, a tool mounted for yielding rotative movement in said holder, and means acting to impart a series of impacts to said holder. 105
9. A shoe shaping machine, having in combination, a holder for a blocking tool, a tool mounted to adjust itself in said holder in ac- 110
- cordance with the position of the work held thereagainst as the point of operation of the tool on the work is transferred thereabout, and means for imparting a series of impacts to said holder. 115
10. A shoe shaping machine, having in combination, a pivotally mounted holder, a blocking tool arranged to swivel therein, a positive stop against which said holder is normally maintained so that the shoe may be pressed against the tool without displacing the holder, a vibratory hammer arranged to strike the holder, and a mechanism arranged to be set in motion by the operator for operating the hammer. 120
11. A shoe shaping machine, having in combination, a blocking tool movable about an external axis, a positive stop acting to determine the initial position of said tool and to support it against the pressure of a shoe presented by the operator, and a spring actuated hammer arranged to operate said tool by a series of percussive impacts. 125
12. A shoe shaping machine, having in combination, a blocking tool mounted to vibrate with reference to a predetermined initial position, a hammer operating to impart recurring impacts to said tool to cause such vibrations, and adjustable means for regulating the impact of the hammer. 130
13. A shoe shaping machine, comprising a substantially horizontal tool holder pivotally mounted at one end and having a blocking tool at the other, a positive stop and a spring for determining the initial position of said holder, a hammer mounted to vibrate above said holder and to swing the holder by impact therewith intermittently downwardly from its initial position, and a cam and spring cooperating to actuate said hammer. 135
14. A shoe shaping machine having, in combination, a tool shaped to conform substantially to the portion of the upper of a shoe adjacent to the last corner, a pivoted hammer, and means for oscillating said hammer whereby a series of impacts is imparted to said tool. 140
15. A shoe shaping machine having, in combination, a tool shaped to conform substantially to the portion of the upper of a shoe adjacent to the last corner, a holder for said tool, a hammer, means arranged to urge said hammer against said holder, and means for successively moving said hammer away from said holder and releasing it whereby a succession of blows is imparted to the tool holder. 145
- In testimony whereof I have signed my name to this specification. 150
